UNITED STATES PATENT OFFICE.

BENJAMIN G. BUNDY, OF NASHUA, NEW HAMPSHIRE, ASSIGNOR TO NASHUA GUMMED & COATED PAPER COMPANY, OF NASHUA, NEW HAMPSHIRE, A CORPORATION OF MASSACHUSETTS.

MANUFACTURE OF GUMMED STRIPS.

Original application filed November 23, 1925, Serial No. 70,887. Divided and this application filed February 25, 1926. Serial No. 90,481.

This application is a division of my application filed November 23, 1925, Serial No. 70,887, which became Letters Patent No. 1,582,449, April 27, 1926.

5 The invention relates to the production of dry gummed sheet material in the form of strips, of the character commonly known as stay strip material which is usually commercialized in the form of coils from which 10 suitable lengths can be severed for use in strengthening the corners of cartons or boxes, or other uses.

It is customary to so make the material with longitudinal marks or scores that when 15 a strip is being applied to use, such as on the corner of a box, it will bend along a mid-width line so that the strip will extend equal distances from the corner onto both sides of the box. Of course a single score 20 line is preferably employed to best effect this result, and said score line should be at the exact mid-width of the strip, regardless of the width of the strip.

One of the objects of the present invention is to produce gummed stay strips having score lines in the gum only, without any weakening of the body (paper or cloth) of the strips, either by cutting into said body or forming grooves therein.

30 Another object is to produce such strips in an economical manner, each with a score line in the gum accurately at its mid-width, whether the strips are narrow or wide. I attain this last mentioned object by effecting the scoring while the sheet material, having a dry coating of gum, is being cut into a plurality of strips side by side. And this is preferably done while said material is being operated upon by what is known as 35 a slitting and re-winding machine one type of which is illustrated in Letters Patent No. 1,484,842, dated February 26, 1924.

With the above-mentioned objects in view, the invention consists in the method 45 and the machine substantially as herein-after described and claimed.

Of the accompanying drawings:—

Figure 1 is a plan view of so much of a 50 slitting machine equipped with my improvements as is necessary to an understanding thereof.

Figure 2 is a side elevation of the same.

Figure 3 is a detail side elevation of the

particular features of my invention which, in the present instance, comprises an attachment to a slitter of the general type illustrated in the Patent 1,484,842 referred to.

Figure 4 is a plan view of a piece of 55 scored strip, as produced according to my invention.

Figure 5 represents a section on line 5—5 of Figure 4, on a scale enlarged to properly 60 illustrate the strip.

Similar reference characters designate 65 similar parts or features in all of the views.

A portion of the frame of the machine is indicated at 12, said frame supporting cutter shafts 13, 14, provided with cooperating disk cutters 15. It is customary in slitting and re-winding machines of the type illustrated in the patent referred to, to vary the 70 number of cutting disks and the spacing thereof along their shafts, according to the widths of the strips into which the sheet α is to be divided.

In the embodiment of my invention illustrated, a roll or smooth-surfaced bar 16 is mounted in the frame of the machine, and the sheet or web α provided with a coating of dry gum passes over said roll or bar on 75 its way to the cutters 15 which divide the web into strips.

Loosely mounted on a tie rod 17 are 80 blocks 18 the positions of said blocks along the tie rod being determined by collars 19 secured to the tie rod between the blocks. Extending through each block 18 is a rod 20 having at one end, above the roll 16, a clamp couple or head 21 in which a sharp-pointed scoring implement 22 is clamped 85 and secured at the proper angle to press on the gum coating and crush it without affecting the layer which carries the gum. In practice I have found phonograph needles to make effective scoring implements. The points thereof bear on the dry 90 gum carried by the web α where the latter travels over the roll or bar 16.

Adjustably mounted on the other end of 95 each rod 20 is a block 23 in which is mounted a rod 24, the said rod 24 extending above the needle-carrying rod 20 and having a weight 25 adjustably mounted thereon. By 100 adjusting the rods and weights, the needles 22 will be caused to bear on the dry gum 105 coating of the web α with more or less pres-

sure according to the character of the gum coating on the web. A thick or very hard coating requires that the needles be caused to bear on the coating with heavier pressure than a thin or soft coating. It is important that the pressure shall be such that the dry gum will be crushed without any cutting or grooving operation on the body layer *b* (Fig. 5) of the web. The construction enables this to be done, so that the paper or cloth layer *b* will not be weakened in any manner by the scoring operation. Practically it leaves the layer *b* uniformly flat from side to side, with two stripes of gum *c* separated by a scored line *a* which exposes the surface of the layer *b*.

To counteract any tendency of the needle-carrying rods 20 to vibrate and result in imperfect scoring, it is desirable that some spring connections be made so that inertia or momentum of the weights will not cause vibrations. To this end I provide a spring 26 connecting each weight rod 24 with a collar 19, and I have also found it desirable to employ a light rubber band to act as a spring for the same purpose. Each rubber band 27 connects a screw 28 of a weight 25 with a hook 29 carried by a transverse rod 30 mounted in the frame of the machine.

The machine is provided with a scoring implement and its carrying members for each strip to be scored and cut. That is, the scoring units equal the strips in number. Each scoring unit can be adjusted along the rod 17 to a position that will locate its needle exactly in line with the middle of the space between cutters that are to determine the width of the strip scored by that needle. In other words, while the needles 22 act on the web before it is cut, the cutters (when they and the scoring units are adjusted according to the intended widths of the strips) sever the web along lines equidistant from the score lines so that each score will be at the exact mid-width of each cut strip.

With the mechanism illustrated and described, it is possible for a machine to produce, simultaneously, scored strips of different widths instead of uniform widths. For instance, some of the disk cutters 15 may be two inches apart and others on the same shafts may be one inch apart. It is then only necessary to adjust the scoring units along the rod 17 so that their needles will be in alignment with the mid-width of the spaces between the cutting disks.

It is to be understood that by the terms needles, and paper, employed herein, I do not limit myself to an exact definition of either term. Any pointed implement capable of effecting the scoring may be used, and the term paper is to be understood as employed for the sake of brevity as applying to any web material. Furthermore, the

term gum is employed as a generic term for any coating that adheres to the web. And of course the scored strips may be employed for purposes other than strictly stay strips.

I do not claim herein the scored strip material which is the product of the method and machine hereinbefore described, as the same forms the subject matter of my application filed November 23, 1925, Serial No. 75 70,887, which application became Letters Patent No. 1,582,449, April 27, 1926.

Having now described my invention, I claim:

1. The method of making stay strip material, consisting in subjecting a coating of dry gum carried by the body of the material to a progressively effected line of pressure tending to crush the dry gum without weakening the body of the material.

2. The method of making stay strips, consisting in cutting a sheet of material having a dry gum coating into a plurality of strips and simultaneously therewith scoring the said coating.

3. The method of making stay strips, consisting in cutting a sheet of material having a dry coating into a plurality of strips and simultaneously therewith subjecting the coating of each strip to pressure along a line at the mid-width thereof.

4. The method of making coated strips with score lines, consisting in cutting a sheet of coated material into a plurality of strips and simultaneously therewith subjecting the mid-width portion of the coating of each strip to a degree of pressure that crushes the said coating.

5. The method of simultaneously producing a plurality of scored strips of coated material, consisting in effecting a plurality of lines of scoring while a web of the material is being cut into a plurality of strips.

6. The method of simultaneously producing a plurality of scored strips of dry-gum-coated material, consisting in causing a web of the material to travel, progressively forming parallel lines of scoring in the coating, and then cutting the web along lines between the scored lines.

7. A machine for operating on a travelling coated web, said machine having cutters for converting the web into strips, and means for scoring the coating on the web on its way to the cutters.

8. A machine for operating on a travelling coated web, said machine having cutters for converting the web into strips, and means for scoring the coating on the web on its way to the cutters, said cutters and scoring means being adjustable relatively to the width of the web.

In testimony whereof I have affixed my signature.

BENJAMIN G. BUNDY.
